UNITED STATES PATENT OFFICE.

WILLIAM MONTGOMERY PERSON, OF SPARROWS POINT, MARYLAND.

COKE-OVEN.

1,079,062.

Specification of Letters Patent. Patented Nov. 18, 1913.

Application filed August 31, 1910. Serial No. 579,897.

To all whom it may concern:

Be it known that I, WILLIAM M. PERSON, a citizen of the United States, of Sparrows Point, in the county of Baltimore and in the State of Maryland, have invented a certain new and useful Improvement in Coke-Ovens, and do hereby declare that the following is a full, clear, and exact description thereof.

10 The object of my invention is to provide a coke oven in which there shall be equal distribution of the gas throughout the length of the oven all the time; an equal distribution of air to all the gas flues that are in 15 operation during a heating period; and an equal distribution of the stack draft to all the ports extracting the products of combustion from the flues that are in action; in which the air for combustion will be delivered at the highest possible temperature at 20 the point of mixture with the gas to be burned; in which wide variations of the temperature of the wall resulting in excessive contraction and expansion will be avoided; in which wind will be without effect on 25 the circulation of the gases and which will have greater strength of wall structure than ovens of which I have any knowledge, and for the attainment of this object and others 30 my invention consists in the coke oven having the construction substantially as herein-after specified and claimed.

In the accompanying drawings—Figure 1 is a longitudinal section of a coke oven embodying my invention, the section being taken on two planes, one passing through the wall on one side of a coking chamber, and the other passing through a coking chamber; and Fig. 2 a cross section thereof 35 on a plane passing through one of the primary regenerators; and Fig. 3 a similar view to that of Fig. 2, but showing only a fragment and on a larger scale.

In the embodiment of my invention in the 40 coke oven selected to illustrate my invention, the coking chambers 10 are as usual long and narrow separated by masonry walls or partitions 11. In each wall or partition 11 there is a series of flues each of an inverted 45 U-shape composed of two parallel vertical passages 12 and 13, respectively, connected at their upper ends by a horizontal passage 14, the corresponding vertical passages of 50 the series of flues being similarly designated 55 in the drawing. Beneath each series of said flues are two horizontally extending gas flues

15 and 16, respectively, that are connected with a suitable main or source of supply of gas, and connected with the gas flue 15 and located at the bottom of the vertical passages 12 are burners 17, while similar burners 18 connected with the gas flue 16 are situated at the bottom of the vertical passages 13, the arrangement being such that gas will be supplied at the same time from 60 the appropriate flue either to all the vertical passages 12 of the inverted U-shape flues, or to all the vertical passages 13 of said flues according to the direction of the draft, which is periodically reversed. Leading 65 into the lower ends of the vertical passages 12 and 13 at the sides thereof, are ports 100 through which air for combustion is supplied for mixing with the gas, or through which the products of combustion find their 70 exit, according to the direction of the draft through the oven. Situated below the respective coking chambers 10, there are supplemental regenerators with which the ports leading to the flue forming passages 12 and 75 13 communicate at the upper ends of the regenerators, said supplemental regenerators being grouped into two series with the regenerators 19 of one series connected with a main or primary generator 20, and the 80 regenerators 21 of the other series connected with a main or primary generator 22, so that there will be a flow of air from one main or primary generator to the series of supplemental regenerators connected therewith, 85 and thence into one of the vertical passages 12 or 13 and the egress of products of combustion through the other vertical passages 12 or 13 to the other series of supplemental regenerators, and thence to the other main 90 or primary regenerator.

By the employment of the supplemental or individual regenerators for each coking chamber, the highest possible temperature is given the air at the point where it mixes with the 100 gas to be burned, while the use of the common or primary regenerator secures a preliminary heating of the air before it comes in contact with the foundation walls of the oven and thereby avoids wide variations of 105 the temperature of the walls. Moreover this preliminary heating of the air enables smaller supplemental or individual regenerators to be used so that the height or elevation of the structure can be reduced. The 110 supplemental or individual regenerators extend longitudinally of the oven, that is, par-

allel with the coking chambers 10, and the series of flues at the sides of the coking chambers. The points of communication between the primary regenerators 20 and 22 and the individual regenerators, are, as clearly shown in Fig. 1, at the midlength of the individual regenerators 19 and 21, as a result of which air resulting from the stack draft is so uniformly distributed through the individual regenerators that a substantially uniform distribution of air is afforded to the series of combustion flues. I have thus equalized the distribution of gas and the distribution of air to the combustion flues.

Describing the operation of my oven with reference to the illustration thereof in the drawing, assuming gas to be supplied to the flues 15, the burners 17 connected therewith will supply gas to be burned to the bottoms of the vertical passage 12 of the inverted U-shaped flues, and air will be supplied to said passages 12 from the primary or main regenerator 20 and thence distributed through the group or series of supplemental regenerators 19 connected therewith. The products of combustion will pass upward through the vertical passage 12 across through the horizontal passage 14 and then downward through the vertical passage 13 and find their exit from the latter through the ports 100 into the group or series of supplemental regenerators 21 and thence to the main or primary generator 22, and thence to the stack. After operating the oven so that the gases will travel as described for a desired period of time, say half an hour, then the gas will be cut off from the flues 15, the direction of the draft changed and then the gas turned on in the flues 16, whereupon a reversal of the flow of gases above described will take place.

The oven illustrated in the drawings embodying my invention, is composed of two like sections or halves capable of independent operation, each half having its own set of primary or main regenerators, but it is within the purview of my invention to employ a single set of primary regenerators for both halves or use simply a stack flue instead of regenerators, although that is not so desirable an arrangement because it would not assure an equal distribution of the stack draft to all the ports because of the necessity of doubling the length of the supplemental or individual regenerators which would result in the production of cross currents that would have a tendency to give the ports farthest from the stack flues less draft than the ports nearer to the stack flue.

The supply of gas and air may be regulated to suit the requirements of the case, so

that, for example, if the coking chamber be tapered the wide end will have the highest temperature. The gas flues are preferably sub-divided by a wall 150 so that there may be several groups of burners, each group having communication with a particular section or sub-division of the gas flue.

Inasmuch as I dispense with the necessity of using a horizontal flue, the oven wall is increased in strength over a construction employing a horizontal flue, and with my construction the unprotected surfaces of the wall are reduced to a minimum.

By my invention a uniform heat from end to end of the oven is secured, the requisites to secure uniform heat being found in my oven and consisting in uniform gas distribution, uniform air distribution, uniform stack draft distribution, and uniform frictional resistance to the passage of air, gas and products of combustion in the combustion flues. I secure uniformity of stack draft by the provision of two separate points afforded by the two pairs of primary regenerators where the stack draft acts, and the location of such points with reference to the combustion flues as to reduce to a minimum the distance to be traveled to the stack or outlet. The greater the distance to be traveled, obviously the greater the variation of the stack draft on the flues and the greater the likelihood of cross currents. As the air, gas and products of combustion in all the combustion flues have the same distance to travel in all the flues, and as the form of the combustion flues eliminates the existence of cross currents, it will be seen that frictional resistance in all the flues must be the same.

Having thus described my invention what I claim is—

1. A coking oven having a plurality of coal-receiving chambers, combustion flues in the wall between contiguous chambers, gas burners for said combustion flues, individual regenerators connected with said combustion flues, and a primary regenerator connected with said individual regenerators.

2. A coking oven having a plurality of coal-receiving chambers, combustion flues in the walls between contiguous chambers, gas burners for said combustion flues, individual regenerators connected with said combustion flues, a set of primary regenerators, and connections between each primary regenerator of a set and a group of individual regenerators.

In testimony that I claim the foregoing I have hereunto set my hand.

WM. MONTGOMERY PERSON.
